Robert Lardenois, Hermes, France, assignor to Valden Company, Toronto, Ontario, Canada

Filed May 16, 1962, Ser. No. 70,161

Term of patent 14 years

(Cl. D9—2)

FIG. 1

FIG. 3

FIG. 1 is a bottom plan view of a brush or the like showing my new design;

FIG. 2 is a side elevational view of the same, the opposite side not shown being substantially the same in appearance, and

FIG. 3 is a top plan view of the same.

My design for the brush disclosed is characterized by the configuration of the curved portions at the juncture of the brush head and handle, in association with said brush head and handle portions, as shown.

I claim:

The ornamental design for a brush or the like, as shown and described.
